US00D811415S

(12) **United States Design Patent** (10) Patent No.: **US D811,415 S**
(45) Date of Patent: **** Feb. 27, 2018**

(54) **STAND FOR HANDHELD ELECTRONIC DEVICE**

(71) Applicant: **Mobile Tech, Inc.**, Lake Oswego, OR (US)

(72) Inventors: **Ed Nelson**, Hillsboro, OR (US); **Mitch Hose**, Hillsboro, OR (US); **Lincoln Wilde**, Hillsboro, OR (US); **Mike Miles**, Hillsboro, OR (US); **Kris Schatz**, Hillsboro, OR (US); **Travis Hooper**, Hillsboro, OR (US)

(73) Assignee: **MOBILE TECH, INC.**, Lake Oswego, OR (US)

(**) Term: **15 Years**

(21) Appl. No.: **29/612,569**

(22) Filed: **Aug. 2, 2017**

Related U.S. Application Data

(63) Continuation of application No. 29/605,791, filed on May 30, 2017.

(57) **CLAIM**

The ornamental design for a stand for handheld electronic device, as shown and described.

DESCRIPTION

FIG. 1 is a first perspective view of a stand for handheld electronic device showing our new design; FIG. 2 is a second perspective view thereof; FIG. 3 is a front view thereof; FIG. 4 is a rear view thereof; FIG. 5 is a left side view thereof; FIG. 6 is a right side view thereof; and, FIG. 7 is a top view thereof.

The broken lines immediately adjacent the shaded areas represent the bounds of the claimed design while all other broken lines are directed to environment and are for illustrative purposes only; the broken lines form no part of the claimed design.

1 Claim, 7 Drawing Sheets
